Primary Examiner — Jennifer Rivard*Assistant Examiner* — Catherine S Posthauer(74) *Attorney, Agent, or Firm* — Gary E. Lambert; David J. Connaughton, Jr.; Lambert Shortell & Connaughton(57) **CLAIM**

The ornamental design for a beverage can protective cover, as shown and described.

DESCRIPTION

FIG. 1 is a perspective view of a beverage can protective cover showing my new design;

FIG. 2 is a top plan view thereof;

FIG. 3 is a bottom plan view thereof;

FIG. 4 is a side view thereof;

FIG. 5 is a side view thereof;

FIG. 6 is a side view thereof; and,

FIG. 7 is a side view thereof.

The broken lines are shown for the purposes of illustrating parts of the article that form no part of the claim.

1 Claim, 3 Drawing Sheets(56)
